LINE TRAP WITH DEMOUNTABLE TUNER

Myron J. Brown, Pittsburgh, Pa., assignor to
Westinghouse Electric Corporation, East Pitts-
burgh, Pa., a corporation of Pennsylvania

Application December 11, 1947, Serial No. 791,041

2 Claims. (Cl. 178—44)

1 My invention relates to a carrier-current line-trap which can be tuned from the ground. A line-trap is essentially a parallel-resonant circuit which is connected in series with a transmission-line conductor as it enters a station, for blocking a carrier-current wave which is used for line-protection, remote-control or metering, communication, or other purposes.

Since the beginning of the use of parallel-resonant line-traps, dating back to about 1930, there has been no provision for tuning such units from the ground. Such line-traps are preferably tuned before being lifted up into position to be connected into the line-circuit; but occasionally it is necessary, due to changed system-conditions, to change the frequency of the carrier-current wave, and this has heretofore necessitated not only taking the line out of service, but also the hazardous, and often extremely difficult, problem of devising some rigging whereby a workman may be elevated up to a position where he can work on the line-trap to change its tuning.

The object of my present invention is to provide a line-trap having a demountable tuner, which can be removed with the aid of a hook-stick or other insulating handling-means, operated from a distance, by a workman on the ground, (or on some elevated structure), while the line is still in service, using a technique which is in some respects similar to that which has been employed heretofore in the removal of line-fuses, hot-line clamps, and the like.

My invention consists in the parts, structures, combinations, systems, and methods of assembly and use, hereinafter described and claimed, and illustrated in the accompanying drawing, wherein:

Figure 1 is a somewhat idealized longitudinal sectional view of a 150 to 300 kilocycle (kc.) line-trap which employs my invention with a demountable attachment of the entire tuning-unit, including the capacitors and a lightning-arrester, the section-plane being indicated approximately by the line I—I in Fig. 2.

Fig. 2 is an end view of the line-trap shown in Fig. 1.

Fig. 3 is a wiring-diagram of the same line-trap, and

Fig. 4 is a fragmentary, somewhat idealized, longitudinal sectional view of a 50 to 150 kilocycle line-trap which employs my invention with a demountable attachment of only the connection-board for the capacitors.

As shown in Fig. 1, the main coil of the line-trap consists of a one-layer winding 5 of strand-

ed copper cable, wound on a porcelain spool 6. The porcelain spool 6 is provided with metal end-brackets 7 and 8, which are connected by strain-rods 9 and a strain-insulator 10 in such manner that line-stresses cannot be transmitted to the porcelain spool 6. Each end-bracket 7 and 8 is provided with a terminal connection 12 (Fig. 2), which receives its end of the coil or winding 5.

There are various ways of mounting a line-trap, the illustrated mounting-means consisting of a set of insulator-supported pipe-elbows 13 and 14 which are connected to eye-bolts 15 in the respective end-brackets 7 and 8, as shown in Fig. 1.

15 In the form of my invention which is shown in Fig. 1, the line-trap is provided with an externally mounted tuning unit 16, which is shown at the left-hand end of the coil. This tuning-unit 16 has a porcelain housing 17 to which metal back (or bottom) and front (or top) covers 18 and 19 are secured. The unit 16 contains a plurality of diagrammatically indicated capacitors 21, of assorted sizes, which are connected between a common bus 22 and a plurality of individual screw-hole terminals 23 which are spaced immediately below a set of corresponding screw-holes 24 in the front cover 19, so that connection can be made from the front cover 19 to any capacitor or capacitors 21 by means of one or more screws 25, as diagrammatically indicated in Fig. 1. The common capacitor-bus 22 is connected to the back (or bottom) cover 18 through a conductor 26. The unit 16 also contains a lightning-arrester 27 which is connected between the front and back covers 18 and 19.

20 In accordance with my invention, the tuning-unit 16 is demountably mounted on the end-bracket 7 of the coil-structure by any means which is susceptible of manipulation through an insulating manipulation-means which is operable from a distance while the line is charged. In the form of construction which is shown in Fig. 1, and which is preferred when the capacitor-unit or structure is light enough to be conveniently handled, the demountable mounting of the capacitor-unit, or tuning-unit, 16, is achieved by means of lower and upper metal brackets 28 and 29, which are carried by the respective end-plates or covers 18 and 19 of the tuning-unit 16.

25 Cooperating with the upper bracket 29 of the tuning-unit 16 is a metal supporting-bracket 31 which is carried by the end-bracket 7 at that end of the coil-structure. The supporting-bracket 31 may conveniently be secured to the end-bracket 7 by the same nuts 32 which engage the ends of the strain-rods 9. The supporting-

bracket 31 has an outwardly bent top portion 33 which terminates in a hook 34 which extends through an elongated slot 35 (Fig. 2) in the upper bracket 29 of the tuning-unit. The supporting-bracket 31 also has an outwardly extending metal post 36 which is welded thereto, and the end of the post 36 abuts against the back of the upper tuning-unit bracket 29 at a point spaced from the hook-receiving slot 35. A demountable electrical and mechanical connection may be provided, between the upper tuning-unit bracket 29 and the post 36, by means of a ring-bolt 37 which is trapped by a trapping-bracket 38 carried by the upper tuning-unit bracket 29, so that the ring-bolt cannot become lost when it is disengaged from the end of the post 36.

The lower bracket 28 of the tuning-unit 16 abuts against the end of another metal post 39, which is shown as extending outwardly from an insulating plate 41 which lies back of the end-bracket 7 at that end of the coil-structure. This insulating plate 41 may conveniently be secured by nuts 42 on the strain-rods 9. The inner end of the post 39 is connected, by a conductor 43, to the other end-bracket 8, at the far end of the coil-structure, so that it is electrically connected to the far end of the coil or winding 5. A demountable electrical and mechanical connection may be provided, between the lower tuning-unit bracket 28 and the post 39, by means of another trapped ring-bolt 47 which is carried by the bracket 28.

The upper bracket 29 of the tuning-unit 16 terminates, at its top, in a ring 57 having an opening of substantially the same size as the openings in the rings of the ring-bolts 37 and 47.

Bird-traps or cover-plates 58 are commonly provided at each end of the line-trap.

In the operation of the demountable tuning-means which is shown in Figs. 1, 2 and 3, it will be understood that the coil 5 of the line-trap is electrically connected in series with a line-conductor L, L, as shown in Fig. 3, but physically the line-trap may be disposed in any position, horizontal, vertical, or inclined, but preferably with the tuning-unit end of the line-trap disposed so that it is most conveniently accessible for dismounting. The terms "upper" and "lower," as hereinabove used, are therefore only convenient reference-terms, applicable to the particular mounting chosen for illustration, and not intended to indicate any limitation in the direction of mounting.

To dismount my tuning-element while the line L is in service, it is convenient to use a hook-stick 60, which is shown in Fig. 1. A hook-stick, as already developed in the art, for somewhat similar hot-wire work, consists of a long wooden pole 61, having some kind of a headed pin 62 on its end. To remove the tuning-unit 16 from the line-trap of Fig. 1, the hook-stick pin 62 is first inserted in the upper ring-bolt 37, as shown in Fig. 1, and this ring-bolt is screwed out of engagement with its post 36, by twisting the hook-stick. Then the lower ring-bolt 47 is similarly disengaged from its post 39. Finally, the hook-stick pin 62 is engaged with the top ring 57 of the upper tuning-unit bracket 29, and the tuning-unit 16 can be disengaged from the hook 34 and lifted down, where it can be retuned, by suitable manipulation of the connection-screws 25 in the front (or bottom) cover 18 of the unit, after which the unit may be replaced by a reversal of the dismounting procedure.

An essential feature of my invention is that

the line-trap shall be provided with a tuning-element which is physically and electrically disengageable therefrom, by an insulating manipulating-means, so that the tuning-element can be removed, retuned, and restored to its original place when the line-trap is in either a horizontal or vertical plane. The line-trap which is shown in Figs. 1, 2 and 3, was designed for the higher range of carrier-current frequencies, so that its entire capacitor-unit, or tuning-unit, 16, was light enough to be conveniently lifted down, with a hook-stick 60, and this procedure was preferred, for such a line-trap, because it entailed the use of only two demountable electrical connections, at the ring-bolts 37 and 47 respectively.

Fig. 4, however, diagrammatically indicates a line-trap which is designed for the lower range of carrier-current frequencies. Here, the capacitors 71 are so large that they have to be mounted inside of the porcelain spool 6 of the main coil 5, and these capacitors are too heavy for practical handling at the end of a hook-stick. In Fig. 4, however, the assorted-size capacitors 71 are electrically connected to busses of a cross-bussed tuning-element 72, of a particular type which is described and claimed in my copending application Serial No. 751,069, filed May 28, 1947, now Patent No. 2,467,727. It is sufficient to say, here, that the tuning-element 72 is the means whereby the capacitors 71 may be connected in many different combinations of parallel, series, and series-parallel arrangements, for tuning the line-trap to different carrier-current frequencies.

In accordance with my invention, as diagrammatically indicated in Fig. 4, the tuning-element 72 is put on the removable part of a two-part electric plug-connector 75, having as many poles as may be needed, preferably a separate pole for each of the terminals of the plurality of capacitors 71 and the coil 5. The tuning-element 72 is normally held in place by a frictional connection, or by any other demountable connection, and it is provided with a demounting loop 77 which can be engaged by a hook-stick so that the tuning-element may be removed, retuned, and replaced, without taking the associated line out of service.

While I have illustrated only two exemplary forms of embodiment of my invention, and while I have illustrated certain exemplary forms of disengageable electrical and mechanical connections, adjustable tuning-arrangements, and insulating remote-control manipulating-means, I wish it to be understood that my invention is not altogether limited to such details, as various changes may be made by way of additions, omissions, and the substitution of equivalents. I desire, therefore, that the appended claims shall be accorded the broadest construction consistent with their language.

I claim as my invention:

1. A line-trap comprising a main-coil structure and a demountable tuning-unit, said main-coil structure comprising a coil, terminal coil-brackets which are electrically connected to the respective coil-ends, a demountable supporting-means at one end of said main-coil structure, said demountable supporting-means comprising two conducting seating-structures, one electrically connected to the adjacent coil-bracket, and the other electrically connected to the far-end coil-bracket, and said demountable tuning-unit comprising a structure including a plurality

of capacitors of assorted sizes, a capacitor terminal-board means whereby a plurality of different capacitors and capacitor-combinations may be connected, and two mounting-bracket elements for opposite terminals of said tuning-unit, said mounting-bracket elements having distance-manipulable mounting-means for engaging the respective seating-structures.

2. The invention as defined in claim 1, characterized by said demountable supporting-means 10 also comprising a hooked supporting-bracket, and said tuning-unit also having a bracket-means having an elongated slot engageable by the hooked supporting-bracket, said tuning-unit also having a distance-manipulable lifting-means for handling the unit when said mounting-means are disengaged from their seating-structures. 15
